The ornamental design for an electrical connector housing, as shown and described.

DESCRIPTION

FIG. 1 is a rear perspective view of the electrical connector housing showing our new design;

FIG. 2 is a front perspective view thereof;

FIG. 3 is a top plan view thereof;

FIG. 4 is a front elevational view thereof;

FIG. 5 is a bottom plan view thereof;

FIG. 6 is a rear elevational view thereof; and,

FIG. 7 is a right side elevational view thereof, the left
side elevational view thereof being a mirror image.Figure 1
